INTERNAL COMBUSTION ENGINE

Filed May 16, 1924

Inventor:
Edward T. Adams;
Attorney
By *John C. Dale*

UNITED STATES PATENT OFFICE.

EDWARD T. ADAMS, OF PHOENIX, ARIZONA, ASSIGNOR TO FAIRBANKS, MORSE & CO., OF CHICAGO, ILLINOIS, A CORPORATION OF ILLINOIS.

INTERNAL-COMBUSTION ENGINE.

Application filed May 16, 1924. Serial No. 713,729.

My invention relates to improvements in internal combustion engines. The object is to provide improved means for forming and introducing expansible charges into the power cylinder of internal combustion engines, especially those using the heavier grades of liquid fuel; improved means for creating and maintaining a body of air under pressure and for delivering said air under pressure to the power cylinder, at the end of the power stroke, in order to secure improved scavenging efficiency; an improved power piston combined with an air compressing piston adapted to be withdrawn, as a whole, from the underside of the cylinder; and improved arrangement of piston, connecting rod, cylinder and supporting frame and relative proportioning and arrangement of said elements to facilitate assembling and disassembling with a minimum of time and expense; an improved combination of primary combustion chamber and power cylinder and cylinder head, and improved means for assembling the same to secure efficiency and accessibility at a minimum of cost.

The invention also includes details in improvements in construction and arrangement.

Referring to the drawings, which illustrate merely by way of example, a suitable embodiment of my invention;—

Fig. 1 is a vertical section.

Fig. 2 is a horizontal section on line 2—2 of Fig. 1.

Fig. 3 is a fragmentary vertical section showing the piston close to the cylinder end.

Similar numerals refer to similar parts throughout the several views.

Referring to Fig. 1, the casting or formation 4 includes the water jacket 5 and the power cylinder 6. Casting or formation 7 includes the air compression cylinder 8, the air receiving chamber or reservoir 9 and the crank case 10. This casting or formation 7 rests upon the supporting base 11, secured to suitable foundations such as 12. The formation or casting 7 is secured to the base 11 in any suitable way, such as by the bolts 13.

The upper end of formation 4 is recessed through the top to receive the element 14, which provides the primary combustion chamber 15, and the channels or passages 16 discharging therefrom the cylinder 6. Into chamber 15 a spray nozzle, such as 17, delivers the preferably atomized liquid fuel.

I have found it advantageous to employ 55 a heating element, as at 17^a, in close proximity to the point of fuel introduction. Other substantially equivalent means may be employed for heating the air near the fuel inlet. 60

As shown in the drawings, Figs. 1 and 3, the cylinder head is preferably formed so as to concentrate the air near the top center thereof, which is in the region of the entry of the fuel into the cylinder, and so 65 that the top of the piston is remote from said fuel inlet, in order to minimize the blast action on the top of the piston. It will also be noted that a portion of the piston comes up close to the outer part of the head, 70 so that approximately fifty percent of the piston diameter has a close clearance with the head. This arrangement causes a blowing action both before and after dead center, and a concentration of the oxygen supply at the top center, which facilitates the 75 mixture of air and fuel and causes a very favorable action on the burning. The convexly curved head and face of piston 23 is of further advantage in directing the scaveng- 80 ing air charge upwardly toward the primary combustion chamber 15, and thus insures that a fresh supply of oxygen displaces the dead exhaust gases therein.

The element 14 is maintained in gas and 85 liquid-tight seal with the casting 4 by means of the block 18 and bolts 19. These bolts 19 comprise long studs rooted deep into the main casting 4, so that the expansion of the studs and of the primary combustion chamber shall 90 be approximately the same. It will be noted that the bolts 19 have a slight clearance as at 20 through a substantial portion of casting 4, and are then threaded, as at 20, into the said casting. 95

The piston member 22, comprises the power piston 23, operating in the power cylinder 6, and the enlarged or stepped portion 24, operating in the air compression cylinder 8. The air compression cylinder 8 is 100 provided with the air intake port 27 and the air discharge port 28; port 27 is connected with the space 29, controlled by the air intake valve 30, and port 28 is connected with the space 31, controlled by the air discharge valve 32. These intake and discharge valves comprise thin metal plates, one opening inwardly to cylinder 8, and the other 105

opening outwardly from said cylinder 8 into the air reservoir 9. The air reservoir 9 delivers, through the upwardly inclined channels 33 and ports 34, to the cylinder 6. The 5 burnt products discharge through the ports 35 to the exhaust manifold 36. Chamber or air reservoir 9 is provided with the large port 37, normally closed by the cover plate 38, as shown. The chamber 39 is provided 10 with the large port 40, having the cover plate 41, spaced slightly away from the walls or margins of opening 40, to form a muffler for the inrushing air to valve 30.

The piston formation 24 also serves in the 15 nature of a cross-head.

The connecting rod 25 is connected at the lowermost part of piston formation 24, as at 26.

The lower end of connecting rod 25 is connected to the crank 42 on shaft 43 provided 20 with the counterbalance 44.

The lower part of frame 7, forming the crank case, has its side openings closed by the plates 45, bolted thereto. It will be noted 25 that the various parts are proportioned relatively so that the skirt of the piston 24 shall not strike the counterbalance 44, and so that the foot 46 of the connecting rod 25, shall not strike the base of formation 7. It is also 30 to be noted that the piston pin is placed so low that the connecting rod can swing to a very wide angle; and the length of the piston 23, which accommodates the upper piston rings 48, is kept down to the smallest 35 safe figure, in order to keep the whole piston short.

By the above arrangement the parts are readily removable as follows:

The element 14 may be removed from the 40 top of the casting or formation 4, by releasing the bolts 19. This gives access into cylinder 6. An eye-bolt, such as 49, is screwed into the top of the piston 23. A line is connected to this eye-bolt to take the weight 45 of the piston and connecting rod 25. The connecting rod 25 is then disconnected at the top of the crank pin box, as at 50. The piston is then lowered by means of the line secured thereto, and, it may be pulled out 50 through one of the openings, normally covered by a plate 45, by pulling on the connecting rod 25 as the piston is being lowered through the cylinder 8.

In replacing the piston and other parts, 55 the reversed process is followed, with the exception, that the plates 38 and 41 and valve plates 30 and 32, are first removed, in order to give access to piston 23, and the piston rings 48, through openings 27 and 28, so that the 60 rings may be pressed back into their grooves, as the piston moves back into cylinder 6. This method of securing access to the piston rings 48, is considered important since otherwise it would be difficult to introduce piston 23 into cylinder 6. It will be noted that the lower

part of the upper cylinder 6 is bevelled, as at 51, in order to facilitate the entry of the rings 48.

In operation:

The method and means for the introduction of combustible charges are preferably in accordance with the general principles described in my co-pending applications as follows:—

Internal combustion engine, filed Oct. 26, 75 1920; Serial No. 419,698

Internal combustion engine, filed Nov. 3, 1921; Serial No. 512,518

Internal combustion engine, filed Mar. 15, 1923; Serial No. 625,185, now Patent No. 1,678,897, July 31, 1928.

In accordance with this general or underlying principle, two zones are formed within the combustion space or spaces: one in which the fuel is more concentrated and not so readily combustible, and one in which the fuel is less concentrated and therefore more readily combustible, whereby the combustion in the less concentrated zone is utilized to cause the complete mixture of the fuel and air in the clearance and the clean burning of the same. The complete combustion is greatly facilitated by the partly recessed or offset cylinder end and the surrounding part close-clearance of the piston, which causes a concentration of air and a blowing action as above described.

The method and combination of means for scavenging the power cylinder, in accordance with the present disclosure, are believed to be 100 new, as follows: The stepped piston 24 compresses the air in the compression cylinder 8 and the air reservoir 9. The compressed air is delivered into the cylinder 6 through the upwardly inclined channels 33 and ports 34, upon the opening of said ports, by piston 23 at or near the end of its power stroke. There is only a single row of these air inlet ports 34, but the upward direction of their 105 discharge serves to ensure distribution of fresh scavenging air to all parts of the cylinder, and this without any deflector on the top of the piston. In other words, by the high pressure air delivered from the reservoir 9, through the sharp upwardly inclined 110 channels and ports 33, 34, even with a substantially flat top piston, as shown, the scavenging is more efficient than by means of the double row of inlet ports or the deflector provided on the piston top, as now commonly 115 used.

What I claim is:—

1. In an oil engine, the combination of a power cylinder, an air compression cylinder with a piston common to said cylinders, said piston having a substantially symmetrical, convexly curved face at one end thereof, means forming a plurality of annularly disposed passages adapted to deliver the compressed air into said power cylinder, the ad- 125

mission of the air being controlled solely by said piston; means including said delivery passages and curved piston face, for initially supplying and directing the compressed air

5 outwardly through said power cylinder, and for effecting an auxiliary scavenging action in a portion of the combustion space, near one end of the piston stroke.

2. In an oil engine, the combination of a 10 power cylinder, an air compression cylinder and a piston adapted to operate in said cylinders, one face of said piston being convexly curved, means forming a reservoir for compressed air around said air compression cylinder, means forming air passages between said reservoir and said power cylinder, the admission of air to said power cylinder being controlled solely by said piston, means including said air passages and said curved piston face, 15 adapted to direct said air at a substantial angle, outwardly toward the head of said power cylinder, and further adapted to effect an auxiliary scavenging action in a portion of the combustion space, near one end of the piston 20 stroke.

3. In an oil engine, the combination of a power cylinder, a primary combustion chamber in connection therewith, and an air compression cylinder, a piston having a portion 30 adapted to operate in said power cylinder and a portion adapted to operate in said air compression cylinder, means connected for driving the piston entirely through its compressor portion, whereby said portion is adapted to 35 serve as a crosshead; the power face of said piston being substantially symmetrical and convexly curved, and adapted thereby to direct compressed air toward said primary combustion chamber, a compressed air reservoir 40 around said air cylinder, a non-return valve operative between said air compression cylinder and said reservoir and means forming channels adapted to deliver compressed air from said reservoir toward said primary com-

45 bustion chamber and against said curved piston face, the admission of said compressed air into said power cylinder being controlled solely by said piston.

4. In an internal combustion engine the combination of a power cylinder, a primary 50 combustion chamber connected thereto, a piston in said cylinder, means for supplying scavenging air to said cylinder, the admission of air being entirely controlled by said piston, the head of said piston being characterized by a smooth, uniformly convex surface, 55 means including the piston head and co-acting with said air supply means, to direct the scavenging air toward said primary combustion chamber near bottom center position of the piston, said means being further adapted to co-act with the cylinder head and primary combustion chamber to cause a blowing action before and after top center position of the piston. 60

5. In an internal combustion engine, the combination of a power cylinder, a primary combustion chamber connected thereto by a plurality of restricted passages, an air compression cylinder, a step piston operating in 70 said cylinders, a compressed air reservoir around said air cylinder, means forming air passages between said air cylinder and the power cylinder, having a trend distinctly toward the primary combustion chamber; the 75 admission of air from said passages into said power cylinder being entirely controlled by said piston, the power face of said piston being symmetrically, convexly curved; means including the curved piston face, and head 80 portion of the power cylinder for directing the air from said passages toward said primary combustion chamber, and adapted to co-act with the cylinder head and primary combustion chamber to cause a blowing action 85 through said restricted passages, before and after top center position of the piston.

EDWARD T. ADAMS.
